(57) **CLAIM**

The ornamental design for a weed torch as shown and described.

DESCRIPTION

FIG. 1 is a rear, left, and top perspective view of a weed torch, showing my new design;

FIG. 2 is a front, right, and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a detailed view taken from the encircled portion labeled "9" in FIG. 1; and,

FIG. 10 is a detailed view taken from the encircled portion labeled "10" in FIG. 2.

The short-dash and long-dash broken lines in FIGS. 1, 2, 9 and 10 denote the boundaries of the detail areas and form no part of the claimed design. The even-spaced broken lines in the drawings depict portions of the weed torch that form no part of the claimed design.
